UNITED STATES PATENT OFFICE.

JOSEPH GIBSON, OF LOS ANGELES, CALIFORNIA.

GAS GENERATOR.

Application filed June 22, 1925. Serial No. 38,753.

This invention relates to gas generators of the type employed in the manufacture of gas from oil, and an object of the invention is to provide a construction that will eliminate to a high degree the formation of soot and carbon.

Another object is to provide for economical generation of the gas.

Another object is to properly distribute the heat to all parts of the gas generator chamber.

Another object is to obtain the proper gas-making temperature in the upper zone where the gas-making nozzles are located, without the necessity of overheating lower zones where combustion is effected.

A further object is to prevent vertical motion of the products of combustion in the combustion chamber.

20 A still further object is to provide a construction that will not deteriorate rapidly and that is of a nature that will permit of use for comparatively large units.

Other objects and advantages will appear 25 hereinafter.

The accompanying drawings illustrate the invention:

Fig. 1 is a sectional elevation of a gas generator constructed in accordance with 30 the provisions of this invention.

Figs. 2 and 3 are horizontal sections on the lines indicated by 2—2, 3—3, Fig. 1.

Fig. 4 is an enlarged sectional detail on a vertical plane of a portion of the generator chamber, showing more particularly the by-pass and ports for effecting heating of the outer parts of the upper zone of the generator chamber.

Referring to the drawings, the generator 40 comprises vertical side walls 5 having flat inner faces and preferably arranged in the form of a polygon having more than four sides. In this instance there are six walls to produce a hexagon. The top 6 of the generator is dome-shaped and the base is indicated at 7. The combustion chambers are indicated at 8, there being two in the present instance and the roofs of said combustion chambers are arcuate, each being 45 formed of a series of spaced arches 9. The arches are held against collapsing laterally by spreaders 10 which also function to keep the arches properly spaced so as to provide vertical passages 11 between adjacent arches. 50 The arches are flat on their upper faces as indicated at 12 and supported on said flat

faces are checkerbrick 13 which partially fill the gas generating chamber 14 to a level indicated at 15. Above the level 15, the gas generating chamber is unobstructed and below said level is provided in its side walls with ports 16 at intervals around the circumference of said chamber. The ports 16 open into an annular vertical passage 17 that is formed in the walls 5 and that extends to the upper face of the arches 9. The passage 17 communicates at its lower end with the vertical inter-arch passages 11 and at its upper end with the vacant space above the checker-brick.

The top 6 is provided with a vent 18 which may be closed by a closure 19. The closure 19 is hinged at 20 or otherwise movably mounted.

Extending through the walls of the unobstructed upper portion of the chamber 14 are oil inlet make nozzles 21 which need not be described and illustrated in detail as their construction is well understood in the art relating to gas generation. The term "make nozzles" is employed in the art and in this specification to designate the nozzles by which the oil and steam that make the gas are admitted to the gas generating chamber.

The combustion chambers 8 are provided with clean-out openings 22 which may be closed by doors 23 of any suitable construction.

Opening through some of the walls 5 are ports 24, each combustion chamber being provided with a pair of ports, and the ports of each pair are positioned diametrically opposite to each other as clearly shown in Fig. 2 of the drawings. In these ports are positioned suitable oil burners 25 which preferably employ an air blast and steam for effective atomization and burning of the oil used in heating the generator.

Communicating with both combustion chambers 8 is a gas off-take 26 to which is connected the pipe, not shown, whereby the oil gas manufactured in the generator is carried to any desired location. The port 26 is positioned at the junction of the two combustion chambers and thus serves to take the combustible oil gas from both of them.

To operate the gas generator described above, the closure 19 will be opened and the burners 25 set into operation. The burners 25 will be operated about fifteen minutes,

more or less, or until the temperature of the walls of the combustion chamber is about 2200° Fahrenheit. It will be noted that because of the burners of each set being diametrically opposed, the blasts from said burners meet mid-way of the combustion chambers, thus deflecting the blasts so that they will not tend to strike the walls 5. Also it will be noted that any of the burning gases that strike the walls 5 will be deflected radially inward toward the more central portions of the combustion chambers, thus protecting the walls 5 from overheating, and consequent rapid deterioration of said walls. Some of the flaming gases that reach the walls 5 will pass directly upwardly through the passage 17 into the unobstructed space above the checkerbrick so that the zone in which the gas-making nozzles are located will be quickly heated to almost as high a temperature as that obtained in the combustion chambers. If the temperature is approximately 2200° F. in the combustion chambers, the temperature in the upper portion of the chamber 14 will be approximately 2100° F.

A large portion of the burning gases passes upwardly through the inter-arch spaces and through the checkerbrick, thus heating the checkerbrick. It will be noted that some of the gases of combustion will pass from the passage 17 through the ports 16 into the upper side portions of the checkerbrick, thus heating such portions to as great a temperature as is obtained elsewhere in the checkerbrick. This prevents the formation of soot and carbon at those portions of the checkerbrick that, without such provision for bringing some of the heat directly from the combustion chambers thereto, would remain at a much lower temperature than the lower and more central portions of the checkerbrick.

After the proper temperature has been obtained, the burners 25 will be shut down and the closure 19 will be closed. Then the oil inlet nozzles 21 will be put into operation to furnish a suitable mixture of oil and steam, from which mixture the gas is evolved by the temperature within the checkerbrick. The oil and steam mixture passes downwardly through the heated checkerbrick and through the inter-arch spaces and the resulting gas is drawn off through the port 26. The gas-making operation will be continued for thirty minutes, more or less, or until the temperature falls below that desirable for the gas-making operation, and the oil nozzles will then be closed. After the generator has been thus heated and a cycle of gas-making operations has taken place, the combustible products remaining in the generator will be supplied with air by turning on only the air at the burners 25 and, after a short interval of time, the

burners 25 will be put into full operation in the usual manner and the cycle of operations above described will again be performed and will be repeated indefinitely.

I claim:

1. An oil gas generator comprising a base, top and side walls, the side walls arranged to form in cross section a polygon having more than four sides, said walls surrounding a combustion chamber and provided with a gas off-take communicating with the combustion chamber, the combustion chamber provided with a roof with passages therethrough, burners positioned diametrically opposite each other in the walls of the combustion chamber, the side walls surrounding an oil gas generating chamber, an oil and steam inlet nozzle in the upper portion of said walls, and checkerbrick in the gas generating chamber extending from the roof of the combustion chamber to below the level of the nozzle. 70

2. An oil gas generator comprising a combustion chamber having a roof formed by spaced arches, a gas off-take for the combustion chamber, the combustion chamber in cross-section being in the form of a polygon provided with more than four sides, burners positioned diametrically opposite each other in the walls of the combustion chamber, an oil gas generating chamber above the combustion chamber, an oil and steam inlet nozzle in the wall of the gas generating chamber, and checkerbrick in the gas generating chamber extending from the arches to below the level of the nozzle. 90

3. An oil gas generator comprising a combustion chamber provided with a roof formed by spaced arches, the combustion chamber provided with a gas off-take, a burner positioned in a wall of the combustion chamber, an oil gas generating chamber above the combustion chamber, an oil and steam inlet nozzle in the wall of the gas generating chamber, checkerbrick in the gas generating chamber extending from the arches to below the level of the nozzle, the wall of the gas generating chamber provided with a vertical passage communicating at its lower end with the inter-arch spaces, and said wall provided with ports opening from the passage into the upper portion of the gas generating chamber. 105

4. An oil gas generator comprising a combustion chamber provided with a roof formed by spaced arches, the combustion chamber provided with a gas off-take, a burner positioned in a wall of the combustion chamber, an oil gas generating chamber above the combustion chamber, an oil and steam inlet nozzle in the wall of the gas generating chamber, checkerbrick in the gas generating chamber extending from the arches to below the level of the nozzle, the wall of the gas generating chamber pro- 115

vided with a vertical passage communicating at its lower end with the inter arch spaces, and said walls provided with ports opening from the passage into the upper portion of the checkerbrick.

5. An oil gas generator comprising a combustion chamber provided with a roof formed by spaced arches, the combustion chamber provided with a gas off-take, a 10 burner positioned in a wall of the combustion chamber, an oil gas generating chamber above the combustion chamber, an oil and steam inlet nozzle in the wall of the gas generating chamber, checkerbrick in the gas generating chamber extending from the arches to below the level of the nozzle, the wall of the gas generating chamber communicating at its lower end with the inter-arch spaces and at its upper end with the 15 gas generating chamber above the checkerbrick, and said wall provided with ports opening from the passage into the upper portion of the checkerbrick.

6. An oil gas generator comprising combustion chambers, each having a roof formed by spaced arches, a gas off-take opening from said combustion chambers, the walls of the combustion chambers together forming a hexagon, burners positioned in

opposite walls of each combustion chamber, 30 a gas generating chamber above the combustion chambers, oil and steam inlet nozzles in the upper portion of the walls of the gas generating chamber, and checkerbrick in the gas generating chamber extending 35 from the arches to below the level of the nozzles.

7. An oil gas generator comprising walls arranged in the form of a hexagon, one of the long diameters of the hexagon dividing 40 the space surrounded by the lower portion of the walls into two combustion chambers, burners positioned in opposite walls of each combustion chamber, each combustion chamber provided with a roof formed of spaced 45 arches arranged on opposite sides of said long diameter, a gas off-take communicating with the combustion chambers, the walls above the combustion chambers surrounding an oil gas generating chamber, oil and steam 50 inlet nozzles in the upper portion of the walls, and checkerbrick in the oil gas generating chamber extending from the arches to below the level of the nozzles.

Signed at Los Angeles, California, this 55
15th day of June, 1925.

JOSEPH GIBSON.
